UNITED STATES PATENT OFFICE.

WILLIAM J. SOMERVILLE, OF CLEVELAND, OHIO.

INKWELL.

1,355,923.

Specification of Letters Patent. Patented Oct. 19, 1920.

Application filed December 29, 1917. Serial No. 209,383.

To all whom it may concern:

Be it known that I, WILLIAM J. SOMERVILLE, a citizen of the United States, residing at Cleveland, in the county of Cuyahoga, 5 and State of Ohio, have invented a certain new and useful Improvement in Inkwells, of which the following is a full, clear, and exact description, reference being had to the accompanying drawings.

10 This invention relates to improvements in inkwells of the sort peculiarly adapted for use in connection with school desks.

The objects of the invention are to provide a neat appearing and highly satisfactory construction for inkwells that is economical of manufacture; convenient of use; durable; and simple of construction.

More generally it provides an inkwell that may be set into the top of a desk or 20 table and which possesses, when closed, no protuberances whereon objects are liable to catch; and wherein the ink container that is usually made of glass or other frangible material is yieldingly supported to protect 25 it against breakage from shock. Furthermore, the construction provides for a comparatively tight sealing of the inkwell when closed.

To these ends the invention may be defined as consisting of the combinations of 30 elements set forth in the claims annexed hereto and illustrated in the accompanying drawing forming a part hereof and wherein Figure 1 is a plan view of my improved inkwell and an adjacent portion of the desk or table top, parts of the inkwell structure being broken away to reveal certain details of construction; Figs. 2 and 3 are sections on the lines 2-2 and 3-3 respectively, of 35 Fig. 1; Fig. 4 is an enlarged sectional detail through the hinge connection of the cover with the top, the plane of section being indicated by the line 4-4 of Fig. 1; and Fig. 5 is a perspective view of the 40 elements of the structure in separated condition.

The desk or table top 1 wherewith my improved inkwell is intended for use, is provided with an aperture 2 that is enlarged downward from its upper end, as indicated 45 at 3, to provide a shoulder 4.

The supporting cap 5 has a cylindrical wall 6 of a diameter to fit within the enlargement 3 of the bore 2, and the lower edge of this wall rests upon the shoulder 4.

At diametrically opposite points, the wall 6 is notched upward from its lower edge, and the material from the notches is turned inward to constitute supporting lugs 7. This is a cheap and convenient way of providing supporting lugs, and being formed of the sheet metal whereof the cap is made, they possess a certain degree of resiliency, a feature of some importance as will herein-after be explained. However, I would be 60 understood as not limiting myself to the exact nature or number of the supporting means or lugs herein shown.

The top, or circular wall, of the cap 5 has an opening 10, shown as located eccentrically of the cap, and extending inward from the sides of an off-set 11 of the opening are opposed projections 12 which constitute a hinge pintle for the cover 15. The cover is of a size and shape to accurately fit within the opening 10, and has an extension 16 that fits the off-set 11; and the extension is transversely grooved at 17 (the groove being preferably formed by depressing the material of the cover) to receive the projections 12. A rivet 20, having a circular head 21 substantially equal in diameter to the extension 16 is arranged to be inserted through a hole 22 in the extension 16, central of the groove 17, and upset therebeyond, as shown most clearly in Fig. 4 thereby to confine the projections 12 within the groove beneath the rivet head, and loosely enough it will be understood to permit the cover to swing with freedom. Attention is called to the 70 fact that the head of the rivet is very shallow and the edge thereof very thin so that, when applied to the cover, its upper surface 75 virtually merges into the plane of the cover and the top of the cap.

Opposed semi-circular flanges 25 extend laterally from the top of an ink container 26, the adjacent ends of the opposed flanges being separated by notches 27. These flanges are identical but are reversely arranged. 80 Their underneath surfaces are inclined to a horizontal plane and at their thickest ends are enlarged as indicated at 28. The flanges, thus formed, constitute cams for engagement with the supporting lugs 7, as will be 85 presently explained.

90 30 is a filler which may be of wood, cork, fiber, rubber, or the like, but preferably compressible, as is the nature of cork. I prefer, also, at the present time, to make it 95 100 105 110

square; and it is adapted to be inserted within the cap with its corners guided within grooves 31, formed by crimping the cylindrical wall of the cap. The filler is thus properly positioned within the cap so that its edge adjacent the hinged side of the cover will not interfere with the operation thereof. The filler has an aperture 33 that is concentric with the opening 10. After the filler has been placed within the cap, the upper end of the container 26 may be inserted, the supporting lugs being passed through the notches 27. Now the container may be turned in a direction to project the thinner ends of the flanges 25 over the lugs 7 and clamp the flanges and filler between the supporting lugs and the top wall of the cap. In this condition, the container is yieldingly supported, due to the resiliency of the supporting lugs and the pliability of the filler. The container is also effectively sealed, except for the opening 11, and this may be closed reasonably tight by the cover 15.

25 When it is desired to open the cover it is only necessary to depress the rear edge of the button-like rivet head 21 to swing the cover upon its hinge; and the cover is held in open condition, as indicated in dotted lines in Fig. 3, by the end of its extension 16 engaging the adjacent side edge of the filler.

Having thus described my invention what I claim is:—

35 1. In an inkwell, the combination of a container, a cap therefor, the cap having inwardly projecting lugs and the container lateral flanges for coöperation with said lugs, the engaging surfaces of the lugs and flanges being inclined one with respect to the other so that reverse relative rotation of the cap and container will draw them together, a filler interposed between the container and cap, the cap and filler having 40 registering openings, and a closure for the opening of the cap that is sustained in closed position by the filler.

2. In an inkwell, the combination of a cap and container having coöperating portions for holding them together, a filler interposed between the cap and container, the cap and filler having registering openings and a closure for the opening of the cap hingedly connected thereto and arranged, 45 when closed, to bear upon the filler.

3. In an inkwell, the combination of a cap and a container having coöperating portions for connecting them, a filler interposed between the cap and container, the cap and 50 filler having registering openings, the opening of the cap having an offset, and a closure for the opening of the cap having an extension within said offset, the closure and cap being pivotally connected at opposed points 55 of the closure extension, the extension of

the closure being adapted to engage the filler to limit the opening movement of the closure.

4. In an inkwell, the combination of a container having opposed substantially 70 semi-circular flanges, the adjacent ends of the opposed flanges being spaced apart to provide notches, a cap for application to the container having diametrically opposed lugs for insertion through said notches and co- 75 operation with the under sides of the flanges, the under sides of the opposed flanges being straight and reversely and gradually inclined, the lower ends of the flanges terminating in enlargements constituting posi- 80 tive stops, a filler interposed between the cap and container, the cap and container having alining openings, and a closure for the opening of the cap.

5. In an inkwell, the combination of a 85 container having opposed semi-circular flanges, the adjacent ends of the opposed flanges being spaced apart to provide notches, a cap having a depending flange and inwardly projecting resilient lugs 90 adapted to pass through the notches and engage the under sides of the flanges, the under sides of the opposed flanges being reversely inclined, a filler of compressible material interposed between the cap and 95 container, the filler and cap having registering openings, and a closure for said openings that is sustained in closed position by contact with a part of the filler projecting within the area of the cap opening. 100

6. In an inkwell, the combination of a container, a cap for attachment thereto, the cap being provided with an opening, a closure adapted to fit into said opening, the closure having a transverse groove and the 105 cap having pivotal means occupying said groove, and finishing means concealing the groove and for confining the pivotal means within the groove.

7. In an inkwell, the combination of a 110 container, a cap for attachment thereto, the cap being provided with an opening having an offset, a closure adapted to fit into said opening and having an extension arranged to occupy said offset, the outer surfaces of 115 the cap and closure being substantially flush when the closure is in closed position, the extension of the closure having a transverse groove and the cap opposed studs which occupy the ends of said groove, and means 120 for application to the outer surface of the extension for closing the groove, the exposed surface of said means being rounded to merge into the surfaces of the closure and cap. 125

8. In an inkwell, the combination of a container, a cap for application thereto, the cap being provided with an opening having an offset, a closure fitting within said opening and having an extension occupying the 130

- offset, the extension being transversely grooved, the cap having diametrically opposed studs extending into the ends of said groove, and a rivet passing through the extension and having a head overlying the groove thereby to confine the aforesaid studs within the groove, the outer surfaces of the closure and cap being substantially flush, and the surface of the rivet head merging into the surfaces of the cap and closure.
9. In an inkwell, the combination of a container, a cap applied thereto, a filler interposed between the cap and container, the cap being provided with an opening having an offset extending beyond the side of the filler, and the filler having an aperture of lesser diameter than the opening and registering therewith, a closure fitting within the opening and having an extension occupying the offset, the extension having a groove and the cap having means extending thereinto, and a button applied to the extension for

confining said means within the groove and serving also as tilting means for the closure, the extension and filler coöperating to limit the opening movement of the closure.

10. In an inkwell, the combination of a container, a cap for application thereto, a filler interposed between the cap and container, the cap and filler having registering openings, a closure for the openings pivotally connected to the cap and having an extension beyond its pivotal connection with the cap for coöperation through a part of the opening of the cover and with a portion of the filler to limit the opening movement of the closure, the cap and filler having co-operating portions for positioning the filler within the cap to maintain its aforesaid portion in proper relation to the extension of the closure.

In testimony whereof I hereunto affix my signature.

WILLIAM J. SOMERVILLE.
